UNITED STATES PATENT OFFICE.

CHARLES W. E. CLARKE, OF NEW YORK, N. Y.

HEAT-BALANCE SYSTEM.

Application filed July 16, 1923. Serial No. 651,881.

This invention relates to steam driven, power generating plants, and it is especially concerned with the auxiliary apparatus that must be used in such a plant.

5 A modern steam driven unit for generating electric power consists of a steam turbine and an electric generator driven thereby. The auxiliaries for such units include exciters, circulating pumps, hot well pumps, 10 vacuum pumps, and the like, and it is the general practice at the present time to drive many of these auxiliary units by motors, the current for this and other station uses being supplied by an auxiliary or station generator driven by a small auxiliary turbine. The exhaust steam from this turbine and from the other steam driven auxiliaries is used to heat the feed water for the boilers. In many cases a motor generator set is floated 15 between the auxiliary generator bus and the main generator bus so that a perfect heat balance may be maintained by transferring the load from one generator to the other. The term "heat balance" is used to designate 20 a condition in which the steam driven auxiliary units supply just the required amount of steam to heat the feed water to the desired temperature without any waste of steam, the feed water absorbing all the latent 25 heat in the auxiliary exhaust steam.

30 This auxiliary or heat balance system has the advantage of being reliable, since the auxiliary units may be cut off from the main system in case any disturbance comes in on the main line. But the initial cost of such a system is high and it is also open to the objection that the auxiliary turbine is relatively small and consequently its efficiency 35 is poor as compared with that of the larger unit.

40 The present invention aims to improve heat balance or auxiliary systems of the general character above described with a view to improving their efficiency, and reducing their first cost, while at the same time retaining all of the advantages of the present 45 systems.

50 The nature of the invention will be readily understood from the following description when read in connection with the accompanying drawings, and the novel features will be particularly pointed out in the appended claims.

Referring now to the drawings,

Figure 1 is a diagrammatic view illustrating a system embodying this invention; and

Fig. 2 is a cross sectional view through a portion of the frame of a generator including both main and auxiliary windings.

In the arrangement shown, steam is generated continuously in the boiler 2 and is conducted through a steam line 3 to a main turbine 4. Mounted directly on the shaft of this turbine are main and auxiliary electric generators 5 and 6, respectively. The main generator delivers current to a main bus 7 and the auxiliary generator delivers current to an auxiliary bus 8 to which the various electrically driven auxiliary units, indicated diagrammatically at 9, 10 and 11, are connected through suitable switching and protective apparatus. These auxiliary units are those required for the operation of the individual turbo-generator, as distinguished from the station auxiliaries, and they may consist of a hot well pump, vacuum pump, motor driven exciter, or any other auxiliaries for this generating unit. It is not proposed to drive the station auxiliaries, such as the boiler feed pumps, force draft fans, stokers, and the like, from the auxiliary generator 6, although this may be done in individual cases if the circumstances make such practice desirable. I consider it preferable, however, to drive these station auxiliaries from another source of current.

Normally the auxiliary bus and main bus are entirely independent of each other, but in order to supply current from the main bus to the auxiliary units 9, 10 and 11, in case of accident to the auxiliary generator 6, I have provided a connecting line 12 between these busses and arranged a switch 14 to control the connection both between the main bus and the auxiliary bus, and also between the auxiliary bus and the auxiliary generator. This switch comprises two switch units with an interlocking connection between them, the arrangement being such that normally the switch closes the line between the auxiliary generator and its bus, as shown in Fig. 1, and keeps the connection 12 open. If the auxiliary generator fails for any reason or its voltage drops below a predetermined point, the electromagnetic controlling mechanism for the switch will operate to open the normally closed connection to the auxiliary bus and

simultaneously close the connection between this bus and the main bus 7. The auxiliaries supplied from the bus 8 therefore, will be kept in operation even if the auxiliary generator 6 should fail.

The exhaust steam from the main turbine 4 is discharged into a condenser 20 and a pump 21 forces the condensate through a feed water heater 22 and into a storage tank 10 or system 23. Another pump 24 forces the feed water from the system 23 through feed water heaters 25 and 26 and a pipe line 27 to the boiler 2. Steam is supplied to the feed water heaters by bleeder connections 28, 29 and 30, respectively, leading from appropriate points in the main turbine 4. The feed water heaters are closed except for suitable vents and drip connections so that the rate of steam flow to them will be controlled automatically by the heat absorbing capacity of the feed water. That is, the bleeder connections are led from the turbine at such points that steam of the proper temperature and pressure will be delivered to the respective heaters to raise the temperature of the feed water by successive steps to the desired degree, and the rate of flow of the steam to the heaters will be controlled by the rate of condensation in the heaters, this rate, in turn, being controlled by the heat absorbed by the feed water, as will readily be understood by those skilled in this art.

Fig. 1 shows the main and auxiliary generators as independent units, but in most situations I prefer to use a dual wound generator. That is, a generator having both main and auxiliary windings in the same armature. Referring to Fig. 2, a portion of a generator armature of the revolving field 40 type is shown at 32. The slots of this armature contain a main generator winding, portions of which are indicated at 33, and an auxiliary generator winding, a portion of which is shown at 34. The nature of this construction will be readily understood by those skilled in this art.

It will now be observed that the system above described is not only fully as reliable as the systems now commonly used, but that it is more economical than present systems, both in first cost and also in operation. The auxiliary turbine which is necessary in prior systems is eliminated entirely, and the dual wound generator is substantially more economical to build than main and auxiliary generators of the same rating. The motor generator set which it has been customary to float between the main and auxiliary busses also is eliminated by this system. At the same time provision is made for taking care of accident to the auxiliary generator. The efficiency of the system is higher than that of present systems since the small auxiliary turbine, which necessarily operates at a low efficiency, is eliminated, and the power which

has been created in prior systems by this turbine is generated in the system here described in a large turbine unit which operates at a high efficiency. A dual wound generator of the character above described also effects 75 economy in the generation of the auxiliary supply of current. The feed water is heated to the desired temperature by steam bled from the main turbine, but no steam can be wasted since the steam flow to the heaters is 75 limited automatically by the heat absorbing capacity of the feed water.

It will be understood that in the foregoing description no effort has been made to give the details of design of the various units 80 since these are matters within the skill of the designer, and they will vary with the circumstances and conditions encountered in each individual installation.

In the system shown an alternating current generator is used and I prefer to use an auxiliary source of alternating current so that the current from the main generator can be used to drive the auxiliary units when desired for any reason. While I prefer to use 90 an automatic switch between the main and auxiliary busses, a manually operated switch is satisfactory for some installations. The stage or stages from which steam is bled obviously will be determined by the requirements of the individual installations. 95

Having thus described my invention, what I desire to claim as new is:

1. In an electric power generating system, the combination of a steam boiler, a generating unit including a steam turbine supplied with steam from said boiler and a generator driven by said turbine and having two windings delivering alternating current to main and auxiliary busses, respectively, 105 a plurality of auxiliary units for said generating unit connected with said auxiliary bus and receiving power therefrom, said busses being normally disconnected from each other, switching mechanism between 110 said busses operative automatically upon the failure of said auxiliary source to disconnect it from said auxiliary bus and to connect said bus with said main bus, steam heaters for the feed water for said boiler, and bleeder connections for conducting steam from a plurality of points in said turbine to said respective heaters, said heaters and connections being arranged to limit the flow of steam to the heaters by the heat absorbing capacity of 120 the feed water.

2. In an electric power generating system, the combination of a steam boiler, a steam turbine supplied with steam from said boiler and driven thereby, main and auxiliary alternating current generators driven by said turbine, auxiliary units arranged to be supplied with power from either of said generators, and an automatic switching mechanism between said generators opera- 130

- tive upon the failure of the generator normally supplying power to said auxiliary units to disconnect said units from the latter generator and to connect them with the 5 other generator.
3. In an electric power generating system, the combination of a steam boiler, a generating unit including a steam turbine supplied with steam from said boiler and 10 main and auxiliary alternating current generators driven by said turbine, said generators being arranged to deliver alternating current to main and auxiliary busses, respectively, a plurality of auxiliary units 15 arranged to be connected with either of said busses to receive power therefrom for operating said units, switching mechanism between said busses operative automatically upon the failure of the generator normally 20 supplying power to said auxiliary units to disconnect said units from one bus and to connect them with the other bus, a plurality of steam heaters for the feed water for said boiler, and bleeder connections for conducting steam from a plurality of points in said 25 turbine to said respective heaters.
4. In an electric power generating system, the combination of a steam boiler, a steam turbine supplied with steam from said 30 boiler and driven thereby, main and auxiliary alternating current generators driven by said turbine, auxiliary units arranged to be supplied with power from said auxiliary generator, and a switching mechanism between said auxiliary and main generators operable to disconnect said auxiliary units 35 from said auxiliary generator and to connect them with said main generator.
5. In an electric power generating system, the combination of a steam boiler, a generating unit including a steam turbine supplied with steam from said boiler and main and auxiliary alternating current generators driven by said turbine, said generators being arranged to deliver alternating 40 current to main and auxiliary busses, respectively, a plurality of auxiliary units connected with said auxiliary bus and receiving power therefrom, switching mechanism 45 between said busses for disconnecting said auxiliary generator from said auxiliary bus and connecting the main generator to said auxiliary bus, steam heaters for the feed water for said boiler, and bleeder connections for conducting steam from a plu- 50 rality of points in said turbine to said respective heaters.
6. A power generating system comprising the combination of a direct-connected turbine and main electric generator, a main power bus connected with said main generator, a steam boiler arranged to supply steam to said turbine, auxiliary power-consuming devices essential to the generation of power associated with said system, an auxiliary power bus arranged to feed said auxiliary power-consuming devices, and means to supply power to said auxiliary power-consuming devices comprising an auxiliary alternating current electric generator associated 60 with said turbine and main generator and driven by said turbine and connected with said auxiliary power bus. 65
7. A power generating system comprising the combination of a direct-connected steam turbine and electric generator, a steam boiler arranged to supply steam to said turbine, auxiliary electric power-consuming devices essential to the generation of power associated with said boiler and turbine, and means to generate the electricity required to operate the auxiliary power consuming devices required for the operation of said boiler and turbine at substantially the same efficiency as the electric power provided for distribution purposes, said means comprising an auxiliary alternating current electric generator directly coupled with and driven by said turbine and arranged to operate said auxiliary electric power-consuming devices. 75
8. In an electric power generating plant, the combination of a steam producing element; a steam turbine driven thereby, a main electric generator directly coupled to the main shaft of the turbine for supplying current to a power consuming system, an auxiliary alternating current electric generator electrically separate from the main generator but also directly coupled to the main shaft of the said turbine and the main generator so that the same turbine that drives the main generator also drives the auxiliary generator; auxiliary power consuming devices essential to the operation of the steam producing element and turbine and connections for driving the same by the electricity produced by the auxiliary generator. 80 85 90 95 100 105
